Geneva, Switzerland, a society of France

Application July 3, 1947, Serial No. 758,815
In Switzerland July 13, 1946

3 Claims. (Cl. 89—191)

1

The invention relates to automatic firearms including a breechblock slideable in a breech casing and cooperating with a system movable longitudinally with respect to said breechblock to ensure, at the end of its forward stroke, temporary locking of the breechblock with respect to the breech casing.

The present invention relates to arms of this kind in which the movable system in question is controlled through driving means carried by the barrel and operated by powder gases from said barrel, said means acting upon the movable system through the intermediate of one or several transmission systems each constituted by a single push-piece slideable in a corresponding housing provided for this purpose in a portion of the firearm rigid with the breech casing.

This construction permits of easily detaching the barrel from the breech casing but it involves disturbances in the working of the breech mechanism due to oscillations of the transmission systems caused by rebounding thereof between the movable system and the driving means above referred to.

The object of the present invention is to obviate this drawback.

For this purpose each transmission system is constituted by at least two independent push-pieces disposed end to end and freely slideable with respect to the breech casing, whereby the rebounding oscillations are quickly damped.

A preferred embodiment of my invention will be hereinafter described with reference to the accompanying drawings, given merely by way of example, and in which:

Fig. 1 is an elevation view, partly in section, of an automatic firearm made according to the invention;

Fig. 2 is a horizontal section on the line II—II of Fig. 3;

Figs. 3 and 4 are cross sectional views respectively on the lines III—III and IV—IV of Fig. 1;

Fig. 5 is a plan view of the locking piece and of the portions of the breech casing with which it cooperates.

The automatic firearm shown by this drawing includes, at the rear of a barrel 10, a breech casing 11 in which is slidably mounted a breech system constituted by the three following elements: a breechblock 12, a locking piece 13 intended to lock the breechblock with respect to the breech casing when a shot is fired and a reciprocating system intended temporarily to keep the locking piece 13 in the breech block locking position. This reciprocating system is consti-

tuted by two sliding plates 14 connected together by a key 15 and slideable longitudinally with respect to the breech casing 11. Key 15 extends through an elongated slot 16 provided in the breech block and carries a firing pin 17 slideable in an axial bore 18 acting also as housing for a recuperator spring 19. The displacement of sliding plates 14 with respect to breech casing 11 is limited by the length of slot 16. Percussion springs 20, interposed between sliding plates 14 and lugs integral with the breechblock, urge said sliding plates 14 forwardly with respect to the breechblock. Locking piece 13 is housed in a recess provided in the lower part of the breechblock. At its front end it includes a cylindrical surface 22, engaged in a housing 23 of the same shape provided in the breech casing and which acts as a hinge. At its upper part, the locking piece is provided with projections 24 intended to engage notches 25 cut in the bottom of sliding plates 14. Its rear face 26 is adapted to cooperate, in the locked position thereof, with a shoulder 27 provided in a cross piece 28 rigid with the breech casing 11.

Locking piece 13 also includes two lateral projections 29 (shown on Fig. 5). The front part of these projections forms inclined surfaces 30 located opposite inclined surfaces 31 disposed on two parts 32 rigid with the breech casing. Inclined surfaces 30 and 31 are intended to come into contact a short time before the breechblock reaches the end of its forward stroke, so as suddenly to drive the rear part of the locking piece downwardly, the front part remaining held in the hinge housing 23. The locking piece then engages, through its face 26, shoulder 27. It is held in this position by plates 14, which slide on the top thereof as they keep moving forward to ensure percussion.

The piece that controls the rearward displacements of sliding plates 14 to release the locking piece after a shot has been fired is constituted by a rod 33 the front end of which forms a cylinder 34 cooperating with a fixed piston 35. This cylinder communicates with the barrel bore through the intermediate of a channel 36 provided in the piston and of a vent 37. Rod 33, which is hollow, is guided at its rear end by a fixed spindle 38 rigid with barrel 10. It is subjected to the action of a spring 39, housed therein, which urges it in the forward direction. The rear part of the rod includes an enlarged portion 40 which is astride barrel 10.

After a shot has been fired, rod 33 produces a rearward movement of sliding plates 14 to re-

lease the locking piece and to permit rearward movement of the breechblock. For constructional reasons and in order to permit of easily taking the barrel apart, the movement of rod 33 is not to be transmitted to the sliding parts through pieces rigid with one of these elements. Use is made of independent transmission systems each constituted by two pairs of push-pieces 41 and 42 unconnected together and freely slidable in two cylindrical housings 43 provided in breech casing 11. Push-pieces 41 are intended to enter into contact with part 40, whereas push-pieces 42 are intended to enter into contact with the front ends of sliding plates 14.

The operation is as follows. In locked position, breechblock 12 is kept in its front position by locking piece 13, sliding plates 14 keep said locking piece in this position and also at the end of their frontward stroke, cause the firing pin to strike the cartridge. Rod 33 is kept in forward position by spring 39 and push-pieces 41 and 42 have but little play left for them between part 40 and the front ends of sliding plates 14. As soon as the projectile has moved past vent 37, gases penetrate into channel 36 and push rod 33 rearwardly. Through push-pieces 41 and 42, this rod causes sliding plates 14 to move rearwardly with respect to the breechblock, thus releasing locking piece 13. Under the effect of the pressure it undergoes from the cartridge case, the breechblock moves backward and pushes said locking piece 13 upwardly. Rod 33 automatically comes back to its frontward position under the action of spring 39, but push-pieces 41 and 42 remain stationary in their rear position until sliding plates 14, in the course of their frontward return movement, on the next closing of the breechblock strike them in the forward direction.

Experience taught that, if each transmission system between part 40 and one of the sliding plates 14 is constituted by a single push-piece instead of several independent push-pieces placed end to end, the forward return movement of sliding parts 14 is seriously interfered with by successive rebounds of this single push-piece.

As a matter of fact, when there is a single push-piece, it is driven forwardly by the corresponding sliding plate, rebounds on part 40, rebounds again on the sliding plate, and so on, and thus performs a series of reciprocating movements which brake the sliding plate and risk reducing the velocity thereof so much that the firing pin fails to work.

In order to obviate this drawback in the firearm according to the present invention, each transmission means between rod 33 and a sliding plate 14 is constituted by a series of push-pieces independent from one another disposed in the same housing. Owing to this arrangement, the forward movement of sliding plates 14 is much less influenced by rebounds of the push-pieces.

As a matter of fact, when one of the rear push-pieces 42 is driven forwardly by the corresponding sliding plate 14, it is itself braked by the impulse it must impart to the front push-piece 41. The latter is driven forwardly, rebounds on part 40, and again strikes the rear push-piece 42. The shock between these two push-pieces has for its effect greatly to reduce their living force. While push-piece 41 starts back in the forward direction, push-piece 42 keeps moving with a reduced velocity. Push-piece 42 may possibly come once more into contact with the corresponding sliding plate 14 but in view of the low velocity and small weight of this push-piece, this new shock will

have but little influence upon the velocity of the sliding plate. Consequently owing to the fact that the transmission between sliding parts 14 and part 40 is ensured not by a single push-piece but by a series of push-pieces of smaller weight which mutually strike one another, rebounds between sliding plates 14 and part 40 are reduced to a minimum and have but a negligible influence upon the velocity of the sliding plates.

10 It is clear that each series may include a greater number of push-pieces and that, in a given series, the push-pieces may be of different respective dimensions.

In a general manner, while I have, in the above 15 description, disclosed what I deem to be practical and efficient embodiments of the present invention, it should be well understood that I do not wish to be limited thereto as there might be changes made in the arrangement, disposition 20 and form of the parts without departing from the principle of the present invention as comprehended within the scope of the appended claims.

What I claim is:

1. In an automatic firearm, the combination of 25 a barrel, a breech casing fixed to said barrel, a breechblock slidable longitudinally in said breech casing, means for locking said breechblock in closed position with respect to said breech casing, said means including at least one piece longitudinally movable with respect to said breechblock, elastic means urging said piece toward the position thereof with respect to said breechblock that corresponds to locking of the breechblock in the breech casing, means operative by powder gases 30 from said barrel for driving said piece away from said position upon firing of a shot, said last mentioned means including a driving part carried by said barrel, operative by powder gases, and at least two push pieces mounted end to end, longitudinally guided in said breech casing and freely 35 slidably therein between said driving part and said sliding piece to transmit the action of said driving part to said sliding piece.

2. In an automatic firearm, the combination of 40 a barrel, a breech casing fixed to said barrel, a breechblock slidable longitudinally in said breech casing, means for locking said breechblock in closed position with respect to said breech casing, said means including two pieces longitudinally 45 movable with respect to said breechblock arranged symmetrically on either side of the longitudinal middle plane of said barrel, elastic means urging said pieces toward the position thereof with respect to said breechblock that corresponds 50 to locking of the breechblock in the breech casing, means operative by powder gases from said barrel for driving said piece away from said position upon firing of a shot, said last mentioned means including a driving part carried by said barrel, operative by powder gases, and at least 55 two push pieces, mounted end to end, longitudinally guided in said breech casing and freely slidably therein between said driving part and each of said sliding pieces to transmit the action 60 of said driving part to each of said sliding pieces.

3. In an automatic firearm, the combination of 65 a barrel, a breech casing fixed to said barrel, a breechblock slidable longitudinally in said breech casing, means for locking said breechblock in closed position with respect to said breech casing, said means including a locking member movably connected with said breechblock and fixed, with 70 respect to said breech casing in locking position, at least one piece longitudinally slidable to a limited extent with respect to said breechblock

adapted, in the course of its forward motion, to bring said member into locking position and to keep it in said position, elastic means urging said piece forwardly with respect to said breech casing, means operative by powder gases from said barrel for driving said piece rearwardly upon firing of a shot, said last mentioned means including a driving part carried by said barrel, operative by powder gases, and at least two push pieces mounted end to end longitudinally guided in said breech casing and freely slideable therein between said driving part and said sliding piece to transmit the action of said driving part to said sliding piece.
